UNITED STATES PATENT OFFICE

JOHN W. RAPP, OF FLUSHING, AND JOSEPH VANORIO, OF BROOKLYN, NEW YORK;
SAID VANORIO ASSIGNOR TO SAID RAPP.

AIRPLANE-RIB.

1,363,997.

Specification of Letters Patent. Patented Dec. 28, 1920.

Application filed January 19, 1918. Serial No. 212,785.

To all whom it may concern:

Be it known that we, JOHN W. RAPP and JOSEPH VANORIO, citizens of the United States, and residents of Flushing, Queens 5 county, New York, and Brooklyn, in the county of Kings and State of New York, have invented certain new and useful Improvements in Airplane-Ribs, of which the following is a specification.

10 This invention relates to improvements in airplane ribs.

The primary object of this invention is to produce from a single strip of sheet metal a complete rib for aerofoil frames.

15 In a more intense aspect our invention comprises the production integrally from a blank of sheet metal of an extremely rigid top longitudinal portion, a similarly rigid bottom longitudinal portion and an inter-

20 mediate web of truss-like conformation, the said portions being so bent as to provide great strength and rigidity and at the same time to have sufficient lightness to meet all the weight requirement for such ribs.

25 Another object of our invention is to enable the production of such airplane ribs with great rapidity and with a minimum number of operations.

In the accompanying drawings, in which 30 similar reference characters designate corresponding parts throughout the several views,—

Figure 1 is a side elevation of a rib embodying our invention;

35 Fig. 2 is another side elevation of a flat metal blank of sheet metal after the same has been trimmed to shape and the interweb apertures and other openings have been cut therein;

40 Fig. 3 is a horizontal section through the center of Fig. 1, looking downwardly;

Fig. 4 is an enlarged fragmentary view of the tail or end portion of a rib, showing in dotted lines that portion of the blank 45 which has been folded down;

Fig. 5 is a horizontal section on the line 5-5 of Fig. 4 looking in the direction of the arrow;

Fig. 6 is a fragmentary view of the front 50 portion of the rib shown in Fig. 1 also showing in dotted lines that portion of the rib which has been folded down;

Fig. 7 is a horizontal section on the line 7-7 of Fig. 6;

Fig. 8 is a section on the line 8-8 of 55 Fig. 6;

Fig. 9 is a section on the line 9-9 of Fig. 6;

Fig. 10 is a section on the line 10-10 of Fig. 1; 60

Fig. 11 is a section on the line 11-11 of Fig. 4.

Referring now to these drawings, which illustrate a preferred embodiment of our invention, 1 (Fig. 2) indicates a blank of 65 sheet metal which has been trimmed at the top portion 2 and the bottom portion 3 to aero-curve shape and in which blank interweb openings numbered 4 to 12 inclusive, preferably oval-shaped in conformation 70 have been cut, leaving web portions 13 to 21 inclusive between or at opposite sides of the said inter-web openings, said interweb portions preferably being gradually arched at opposite sides to provide the 75 minor arc portions of said oval openings and to blend with the top and bottom portions, the whole conformation being what we shall term, "a truss-like conformation." Said blank is also preferably provided with suitable perforations numbered 22 to 29 inclusive 80 to permit connections to be made with other parts of the aerofoil frame, and suitable notches 13^a and 21^a are also preferably made in the blank to enable the formation 85 of seats at opposite ends for the marginal frame parts.

The blank 2 is preferably, in the fewest possible number of operations folded or bent as follows: The top and bottom marginal 90 edges are bent or folded down longitudinally to provide a longitudinally extending hook-shaped bead 30 at the top and a similarly shaped bead 31 at its bottom longitudinal portion, as illustrated more particularly in Figs. 95 1, 4, 6, 8, 9, 10 and 11, Figs. 4 and 6 showing in dotted lines the folded portion of the blank. These beads 30 and 31 each comprise a neck portion which inclines outwardly to one side of the vertical plane of the blank, 100 a side portion at said side of the plane of the blank, a substantially flat top portion which crosses horizontally the vertical plane of the web of the blank, and a downwardly extending marginal flange portion which extends and hangs downwardly at the opposite side of said vertical plane. These beads not 105 only provide sustaining surfaces for the can-

vas or other covering of the aerofoil, but also form symmetrical longitudinal portions which greatly increase the strength of and reinforce the other parts of the rib. The 5 edges of the openings 4 to 12 inclusive are also folded to provide continuous oval-shaped flanges 32 surrounding said openings and such flanges are preferably folded in the same direction as the beads 30 and 31 10 are folded. This folding of the continuous flanges 32 will be best understood from an examination of Figs. 3 to 7 inclusive, Figs. 4 and 6 showing in dotted lines the portion of the blank which was folded to form the 15 flange 32. It will be obvious that these folded flanges 32 so formed with continuity around the interweb openings will greatly reinforce the strength and rigidity of the rib construction.

20 The said blank is also preferably further reinforced and strengthened by providing in each web portion of the blank, an embossed or raised bracing portion which extends inwardly in the same direction as the continuous 25 flange 32 and to substantially the same depth, whereby a web portion of great strength and rigidity is provided, which web portion in combination with the top and bottom longitudinally-folded beads 30 above described produce an extremely strong and rigid rib construction which will have sufficient lightness to meet all requirements as to weight for use in airplanes.

Provision in the blank 2 is also made at 35 suitable points along the length thereof for the formation of integral shelves or brackets 33, 33^a and 34, 34^a for the connection to the rib of spars or cross members of the wing or other aerofoil part in which our improved 40 rib is employed. As shown, these integral shelves or brackets comprise inward extensions of the said continuous flanges 32 and these brackets are provided with perforations 22, 23 and 28 and 29 formed in the 45 blank for the purpose of permitting ready connection to a spar or the like.

It will be seen that we have, from a single strip of sheet metal provided longitudinally folded or bent top and bottom portions, continuous 50 arch or oval-shaped flanges surrounding similarly shaped openings, and transversely extending embossed strengthening braces, and that these folds or bends are all symmetrically related or in substantially

the same planes, and combined together give 55 a maximum of strength and rigidity for a given weight of metal.

Having described our invention, we claim:

1. A rib for aerofoils formed complete from a single strip of sheet metal and embodying a top longitudinally-folded portion, a bottom longitudinally-folded portion, intermediate portions having connecting webs provided with embossed bracing struts extending in the direction of said folded portion and web openings provided with continuous embossed marginal flanges also extending in the direction of said folded portions and end portions adapted to abut against frame members of the aerofoil. 60 65 70

2. A rib for aerofoils embodying top and bottom longitudinally-folded portions, each comprising hook-shaped beads formed by folding the upper and lower marginal edges of a blank of metal longitudinally to provide flat canvas sustaining portions and downwardly extending marginal flanges, and intermediate portions having connecting webs and inter-web openings, all formed integrally in said blank. 75 80

3. A rib for aerofoils embodying a top longitudinally folded portion, a bottom longitudinally-folded portion, each comprising hook-shaped beads formed by folding the upper and lower marginal edges of a blank 85 of sheet metal longitudinally to provide flat horizontally-disposed canvas-sustaining portions and downwardly-extending marginal flanges, an intermediate portion having inter-web openings oval-shaped in conformation, continuous flanges surrounding said openings and extending transversely of said top and bottom longitudinally folded portions, and webs between said openings having embossed braces stamped up therein in 90 the same direction as said continuous flanges, whereby the metal of said web portion is arranged symmetrically beneath the said top and bottom folded portions. 95

Signed at College Point, in the county of 100
Queens and State of New York, this 8th day
of January, A. D. 1918.

JOHN W. RAPP.
JOSEPH VANORIO.
